UNITED STATES PATENT OFFICE.

HIRAM RUSHTON, OF TORONTO, ONTARIO, CANADA.

STEAM-BOILER CLEANER.

SPECIFICATION forming part of Letters Patent No. 360,821, dated April 5, 1887.

Application filed August 21, 1886. Serial No. 211,497. (No model.)

To all whom it may concern:

Be it known that I, HIRAM RUSHTON, of the city of Toronto, in the county of York, in the Province of Ontario, Canada, boiler-maker, 5 have invented certain new and useful Improvements in Steam-Boiler Cleaners, of which the following is a specification.

The object of the invention is to design a device by which mud or any solid matter will 10 be prevented from collecting around the tubes and bottom of the boiler; and it consists in forming a long narrow chamber on the inside of the boiler, immediately over the hole through which the feed-water enters, the said 15 chamber being sufficiently narrow to fit between the boiler plate and tubes, and it is shaped to extend from the lower portion of the boiler below the tubes to a point slightly above high-water mark, a trough-shaped top 20 being formed on the chamber with a series of slanting partitions arranged to cross the trough so as to leave only small openings between the trough and the interior of the water-chamber, substantially as and for the purpose 25 hereinafter more particularly explained.

Figure 1 is a perspective view of the locomotive-boiler partially broken away to expose my device. Fig. 2 is a vertical end section through X Y. Fig. 3 is a perspective detail 30 of the chamber removed from the boiler.

In the drawings, A represents a long narrow chamber shaped so as to fit into the boiler within the space left between the tubes and shell of the boiler. This chamber A communicates with the pipe B, extending along its 35 entire length, a slot being made in the pipe B, so as to leave a clear passage-way between its interior and that of the chamber A. One end of the pipe B is carried through the shell of 40 the boiler, and has a blow-off cock, C, fitted onto it.

D is a feed-pipe provided with the ordinary check-valve, and entering the chamber A at a. b is a deflecting-plate placed over the feed- 45 pipe entrance a, so that the water entering through the said feed-pipe will be directed down toward the bottom of the chamber A. At the top of the chamber A a trough, E, is formed having a series of deflecting-plates, F, 50 arranged to cross it, as indicated, so as to par-

tition said trough and leave only a series of small openings between the interior of the trough and that of the chamber A.

The operation of my improved device is as follows: The feed-water, entering at a, strikes 55 the deflecting-plates b, and is thrown toward the bottom of the chamber A, where the mud or any foreign matter entering with the water will naturally settle. When the level of the water reaches the holes e, made in the end of 60 the plates f of the trough E, it will flow into the boiler, and as the deflecting-plate F separates the end portion of the trough E from the main body of the water within the said trough, and as the water which will pass 65 through holes e must come from the chamber A through the small opening g, the scum which may form on the surface of the water within the trough will not pass through the holes e, but will finally settle to the bottom of the 70 chamber A and escape through the pipe B when the blow-off cock C is open. As I purpose that the chamber A should be blown off as often as the engineer in charge may deem necessary, I provide a blow-off cock, C, with 75 a rod, G, extending back to the cab of the locomotive, or, if the boiler is a stationary one, to a convenient point, so that the engineer may blow off the chamber A without danger of being scalded. 80

While my device has been specially designed for locomotive-boilers, it is equally applicable to stationary boilers or to any other class of steam-boilers.

As locomotive-boilers are fed from both 85 sides, I provide two chambers, A, both being arranged in the manner herein described.

What I claim as my invention is—

1. A chamber, A, fitted onto the inner side of the shell of the boiler and arranged so that its 90 interior shall communicate with the feed-pipe D, in combination with the pipe B, provided with a blow-off cock, C, arranged substantially as and for the purpose specified.

2. A chamber, A, fitted onto the inner side 95 of the shell of the boiler and communicating with the interior of the pipe B, which is provided with a blow-off cock, C, as specified, in combination with a feed-pipe, D, communicating at a with the interior of the chamber A, 100

and having a deflecting-plate, *b*, located substantially as and for the purpose specified.

3. A chamber, *A*, fitted onto the inner side of the shell of the boiler and arranged so that its interior shall communicate with the feed-pipe *D*, in combination with a trough, *E*, formed on the top of said chamber, and having a series of deflecting-plates, *F*, and holes

e, made in its end plate, *f*, above the bottom of said trough, substantially as described.

Signed at Toronto, August 7, 1886.

H. RUSHTON.
